to General Electric Company, a corporation of
New York

Filed June 2, 1966, Ser. No. 2,512

Term of patent 14 years

(Cl. D26—5)

FIG. 3

FIGURE 1 is an end elevational view of a dynamoelectric machine employing my new design;

FIGURE 2 is a plan view as seen from the top in FIGURE 1;

FIGURE 3 is a side elevational view as seen from the right in FIGURE 1; and

FIGURE 4 is an end elevational view of the dynamoelectric machine as seen from the rear in FIGURE 1.

The view taken from the bottom of FIGURE 1 is substantially similar to FIGURE 2.

I claim:

The ornamental design for a dynamoelectric machine, substantially as shown and described.
